UNITED STATES PATENT OFFICE.

HARRY B. CURTIN, OF GRAFTON, WEST VIRGINIA.

DESIGN FOR A CAKE OF SOAP.

SPECIFICATION forming part of Design No. 27,959, dated December 7, 1897.

Application filed April 17, 1895. Serial No. 546,133. Term of patent 14 years.

To all whom it may concern:

Be it known that I, HARRY B. CURTIN, a citizen of the United States, residing at Grafton, in the county of Taylor and State of West Virginia, have invented a certain new and original Design for Soap Cakes, of which the following is a specification, reference being had therein to the accompanying drawings.

10 In the drawings, Figure 1 is a perspective view, and Fig. 2 a cross-section on the line 2 2 of Fig. 1.

As shown in the drawings, the leading feature of my design consists in an oblong cake 15 having its upper and lower faces, as well as its sides and ends, flat, said side faces and end faces being approximately vertical and having a continuous groove cut in them midway the depth of the cake, said groove con-

tinuing around the cake without interruption and being semicircular in cross-section and the vertical corners being slightly rounded off vertically, as more fully hereinafter set forth.

Referring to the drawings by letter, *a* represents the upper and lower flat sides of the cake; *b*, the vertical side faces; *c*, the vertical end faces; *d*, the continuous groove, and *e* the four vertically-rounded corners.

What I claim is—

The design for a cake of soap substantially as herein shown and described.

In testimony whereof I affix my signature in presence of two witnesses.

HARRY B. CURTIN.

Witnesses:

CHARLES D. DAVIS,
CHAS. A. MUZZY.
